UNITED STATES PATENT OFFICE.

JOSEPH F. BANISTER, OF TITUSVILLE, PENNSYLVANIA.

STEAM-VALVE.

SPECIFICATION forming part of Letters Patent No. 247,985, dated October 4, 1881.

Application filed February 16, 1881. (Model.)

To all whom it may concern:

Be it known that I, JOSEPH F. BANISTER, a citizen of the United States, residing in the city of Titusville, in the county of Crawford 5 and State of Pennsylvania, have invented a new and Improved Steam-Valve, of which the following is a specification.

My invention relates to improvements in the arrangement of valves and ports in steam-pumps, for removing the friction of a portable or movable valve-seat, and to secure the movements of the main and plunger valve.

Figure 1 represents a longitudinal sectional view of my improvements, showing the valve-seats and ports. Fig. 2 represents a top view of the valve-seats and ports. Fig. 3 represents a transverse sectional view of the same. Fig. 4 represents a detail perspective view of the main valve. Fig. 5 represents the small movable valve G, with a projection on its upper side, in which is a notch, H. In this notch a projection, I, on the main valve M fits. (See Fig. 4.) This small valve G is moved by the valve-rods C C, which valve-rods are moved by the levers B B. The levers B B are moved or operated by the tappet-rods D D, which are moved by the piston-head X in its forward and backward stroke.

F F, Fig. 1, represent the auxiliary pistons 30 that operate the main valve M. The center part, connecting the auxiliary piston at K, is reduced in size to fit into a concave slot in the top of the main valve M. By this means the main valve M is operated. The auxiliary pistons are operated by the steam let on by the small valve G through the ports W W.

4 and 6, Fig. 1, show the main steam-ports, and 5 the exhaust-port. These ports are also shown in the valve-seat N, Fig. 2.

P shows the seat of the small valve G, which 40 admits the steam to auxiliary pistons F F through the ports 1 and 3. (See Fig. 2.) W W are steamways or continuations of these ports.

2 is the exhaust-port to the small valve G. In case the auxiliary pistons F F should stick, 45 from rust or other cause, then they would be started by the movement of the small valve G, which, by means of the notch H and the lug or projection I on the main valve M, would operate the auxiliary piston F F. The notch 50 H is the width of the steam-port 4 or 6 wider than the lug I. This gives the main valve M the full throw of the ports, unless the auxiliary pistons F F stick, when it would be started by the notch on the valve G coming in contact 55 with the projection or lug I on the main valve M.

I claim—

1. Valve M, having projection I, in combination with valve G, having recess H, and operating in the manner substantially as set forth. 60

2. In combination with valve M, having projection I, and valve G, having recess H, of piston X, tappet-rods D D, levers B B, and pistons F F, with their necessary steam passages and ports, all arranged substantially as set 65 forth.

JOSEPH F. BANISTER.
